(57) **CLAIM**

The ornamental design for a tray, as shown and described.

DESCRIPTION

FIG. 1 shows a perspective view of the tray of the present invention.

FIG. 2 shows an overhead view of the tray of the present invention.

FIG. 3 shows an underside view of the tray of the present invention; and,

FIG. 4 shows a side view of the tray of the present invention. The broken lines shown in the drawings represent environmental effects or potential embodiments and do not form any part of the claimed design.
